(57) **CLAIM**

The ornamental design for a pet leash, as shown and described.

DESCRIPTION

FIG. 1 is a top, front perspective view of a pet leash, showing our new design;

FIG. 2 is a bottom, rear perspective view thereof;

FIG. 3 is a front view thereof;

FIG. 4 is a back view thereof;

FIG. 5 is a top view thereof;

FIG. 6 is a bottom view thereof;

FIG. 7 is a left view thereof;

FIG. 8 is a right view thereof; and

FIG. 9 is a top, front perspective view of the pet leash of FIG. 1, shown in a condition for use with an attachment clip. In FIG. 9, the broken line showing of an attachment clip depicts environmental structure and forms no part of the claimed design.
